[57] CLAIM

The ornamental design for a foldable table, as shown and described.

DESCRIPTION

FIG. 1 is a top plan view of a foldable table, showing my new design;

FIG. 2 is a side elevational view on an enlarged scale, the opposite side being a mirror image thereof;

FIG. 3 is a side elevational view on an enlarged scale of the foldable table in folded condition;

FIG. 4 is a sectional view taken along the line 4—4 of FIG. 2 and looking in the direction of the arrows thereof;

FIG. 5 is a bottom perspective view.

FIG. 1.

FIG. 4.

FIG. 3.

FIG. 2.
